UNITED STATES PATENT OFFICE.

EDWIN R. CAHOONE, OF NEWARK, NEW JERSEY.

HARNESS-SADDLE TREE.

SPECIFICATION forming part of Letters Patent No. 223,989, dated February 3, 1880.

Application filed October 13, 1879.

To all whom it may concern:

Be it known that I, EDWIN R. CAHOONE, of the city of Newark, county of Essex, and State of New Jersey, have invented a new and useful Improvement in Harness-Saddle Trees, of which the following specification is a description.

The nature and object of my invention is the production of a tree that will make a saddle 10 cheap, strong, handsome, and of great utility, having long jockeys, thus doing away with the back-band loops and the necessity of a full pad.

One of the features of my invention is to obtain removable ornamental ends to the jockeys. 15 Such ends fasten to the flaps and, by means of a hook on the ends of the jockeys, are kept in their place when the adjustable metal loops are in their place also. These ornamental 20 ends, by being removable, can be plated with silver, nickel, or gold, as may be desired, and can also be used when it is desirable to have the jockeys of leather. In this exhibit they are of metal made in imitation of leather.

Another object is to get the terrets a little 25 wider from each other, which is very essential for trotting purposes. In such case the removable ends form a protection to the leather jockeys, as they are so long as not to need 30 back-band loops.

In order that others skilled in the art may be able to understand my invention, I will now proceed to describe its construction and operation.

Figure I is a top view of my saddle-tree, 35 showing one half, the other half being the same, representing the housing A, to which the padding leather is attached with the same stitching, both being bound together with ornamental 40 binding, the jockeys B, the terret C, ornamental ends D, side pieces, G, seat H, check-hook I, and jockey-hook J.

Fig. II is a cross-section of Fig. I, cut lengthwise through the center on a line, xx , showing 45 all the parts put together when finished, except the padding, housing A, jockeys B, terret C, ornamental ends D, iron back-band loops E, back-bands F, side pieces, G, screw K, under pieces, L, burrs M.

Fig. III is a top view of the under pieces, L,

showing the aperture O, to insert the terret-burrs M, the slotted hole P, to admit the threaded part of the burrs, and the hole Q, for the screw which fastens the parts together.

Fig. IV is a view of the under side of the 55 loop E, to which the back-bands are sewed, showing the aperture G G, to receive the hook on the end of the jockey, and screw-hole i i for fastening.

Fig. V is a top view of the ornamental removable ends D, showing the arms S, with holes f f for fastening.

Fig. VI is a longitudinal section of a part of the jockey, showing its hook in elevation.

A represents the housing or top part of the 65 pad, to which the leather that forms the stuffed part and the binding are sewed. B is the jockey, which in this case is of metal, but is sometimes covered with leather. C is one of the terrets. D is the ornamental removable 70 end, made of silver, nickel, or gold, as may be desired. E is the metal loop to which the back-bands are sewed. F is the back-bands. G is the side piece. H is the seat. I is the check-hook. J is the hook on the end of the 75 jockey. K is the screw which secures the parts together. L is the under piece, having the aperture O for receiving the burrs for putting in the mountings after the saddle is made, the countersunk screw-hole Q for the screw K, 80 which fastens the loop E, side pieces, G, ornamental removable ends, and housing A together, in conjunction with the hook J, burrs M, and terret C. M is the terret-burr. O is the aperture in the under piece, L, to receive the 85 burrs to convey them to the slotted hole P when the trimmings are put in after the saddle is made. Q is the hole for the screw K, which fastens the under piece to the other frame, in conjunction with the other appurtenances. S S are the arms on the ornamental removable ends, in which are holes f f for 90 fastening to the frame and flaps.

A similar device to the hook on the end of the jockey has been used before; but that was 95 on the end of an iron back-band, while mine is on the end of the jockey, performing quite a different office.

Ornamental ends have been used on saddle-trees before; but they have been rigidly cast 100

to the tree, while mine are separate, and can be used or not at pleasure; also, something resembling ornamental ends has been used on the ends of coach-pads; but they have had 5 loops on them performing an altogether different office.

Iron jockeys are old; but mine are elongated for a special purpose, which is to do away with the back-band loops and allow of the terrets 10 being kept wider apart, so as to be desirable for trotting-harness.

Having thus fully described my invention, what I claim, and desire to secure by Letters Patent, is—

1. A harness-saddle having removable ornamental ends D, provided with perforated fastening-arms S S, substantially as and for the purpose described. 15

2. In a harness-saddle tree, the combination of the elongated jockeys, the hooks J thereon, 20 the removable ends D, having arms S, and the loops E, all substantially as shown and described.

EDWIN R. CAHOONE.
